Inventor

Carl E. Skoog,

By Horatio E. Bellows.

Attorney

UNITED STATES PATENT OFFICE.

CARL E. SKOOG, OF CRANSTON, RHODE ISLAND, ASSIGNOR TO GARTNER & SKOOG, A FIRM CONSISTING OF HIMSELF AND GEORGE C. GARTNER, OF PROVIDENCE, RHODE ISLAND.

SEPARABLE BUTTON.

Application filed October 18, 1923. Serial No. 669,199.

To all whom it may concern:

Be it known that I, CARL E. SKOOG, a citizen of the United States, residing at Cranston, in the county of Providence and State 5 of Rhode Island, have invented certain new and useful Improvements in Separable Buttons, of which the following is a specification.

My invention relates to buttons of the separable type, and particularly to cuff buttons 10 and other fastening devices.

The essential objects of my invention are facility of manipulation; security against accidental escape; and inexpensiveness of construction.

15 The invention consists in the means and mechanism for producing the results above specified substantially as hereinafter claimed.

In the accompanying drawings which illustrate the principle of this invention and 20 constitute a part of this specification.

Figure 1 is a side elevation, partially in vertical central section, of a cuff button embodying my invention, showing the parts in locked position,

25 Figure 2, a like elevation of the same showing the parts in position of partial withdrawal, and Figure 3 a transverse section on line 3—3 of Figure 1.

Like reference numerals indicate like parts 30 throughout the views.

In the construction illustrated the button comprises a master member 5 and a receiving member 6. The latter comprises a head plate 7 with a hollow retracted neck 8 upon 35 whose flaring inner end is a base or end plate 9 having a peripheral flange 10 engaging the shank by a rolled over bead 11. In this instance a reinforcing plate 13 is frictionally held between the end plate and 40 shank, but this may be omitted or constitute an integral part of the plate 9. The plates 9 and 13 have central holes 15 and 16 respectively.

The master member 5 comprises a head 45 plate 18 having a central perforation 19, a hollow double tapering shank 20 fast thereto; and an end plate or base 22 engaging the inner flared end of the shank by a bead 23, and provided with a central opening 25.

50 Rigidly fixed in this opening by friction, solder, or otherwise intermediate its length is a cylindrical block or plug 27 provided with a central vertical bore 28 and with a centrally transverse or diametrical bore 29

55 extending to the exterior of the block but of

slightly less diameter at its ends to form an annular retaining shoulders 30. An operating rod or plunger 32 is slidable in the perforation 19 and bore 28, having in this instance a head portion 34. Near its bottom is an 60 annular groove or recess 35. A helical spring 37 surrounding the rod has its lower end in contact with the member 27 and its upper end abutting against a shoulder or ring 38 integral with or fixed to the rod. In the 65 bore 29 at opposite sides of the rod 32 are slidably mounted metal balls or spherical members 40 of such diameter that when their adjacent portions are in contact with the member 32 their remote portions project laterally from the member 27; but when the members 40 are in contact with the rod in the groove 35 they do not laterally project.

To operate the button, the members 5 and 6 are engaged or disengaged with each other 75 by inserting or withdrawing the member 27 into or from the member 6 through the holes 15 and 16. During the instant of insertion or withdrawal the operator manually depresses the rod 32 whereby the groove 35 is 80 placed in the horizontal plane of the members 40, and the latter are induced inwardly into nonlocking position, as shown in Figure 2. During the locking operation, after the balls have reached a position completely 85 below the plates 9 and 13, and the rod 32 has been released by the operator, the spring elevates the rod and the nongrooved portion of the latter engages the members 40 and causes them to laterally project from the 90 member 27, as shown in Figures 1 and 3. Thus the members 5 and 6 are interlocked.

I claim:

1. A separable button formed in two parts, each having a shank, a head, and a base, one base being provided with a central hole, a projecting block fixed on the other base slidable through the hole and provided with a longitudinal bore and a transverse bore, a plunger slidable in the longitudinal bore and provided with a groove normally remote 100 from the transverse bore, and locking members slidably mounted in the second bore normally projecting laterally from the block into the path of the first base, and registerable in the groove when the plunger is moved and when the members contact with said first base.

2. A separable button formed in two parts, each having a shank, a head, and a base, one 110

base being provided with a central hole, a block fixed on the base of the second base slidable through the hole, and provided with a diametrical bore, a plunger yieldingly mounted 5 in the block transversely of the bore provided with a groove out of alignment with the bore, and spherical locking members loose in the bore in the path of the first base and adapted to enter the groove when the 10 plunger is depressed.

3. A separable button formed in two parts, each having a shank, a head, and a base, the base of one part being provided with a central hole, and the head of the other part being provided with a central perforation, a 15

block fixed on the base of the second part slidable through the hole in the base of the first part and provided with a longitudinal bore and a transverse bore, a plunger slidably mounted in the first bore and extending through the perforation and provided with a groove out of alignment with the second bore, locking members in the second bore normally in contact with the ungrooved portion of the plunger and projecting into the 20 path of the first base, and a spring engaging the block and the plunger.

In testimony whereof I have affixed my signature.

CARL E. SKOOG.
